FUEL COMBUSTION RATE INTENSIFIER

Filed Feb. 19, 1924

INVENTOR.
ALBERT J. SIEVERS
BY *Joseph B. Gardner*
ATTORNEY.

UNITED STATES PATENT OFFICE.

ALBERT J. SIEVERS, OF OAKLAND, CALIFORNIA.

FUEL-COMBUSTION-RATE INTENSIFIER.

Application filed February 19, 1924. Serial No. 693,948.

My invention relates to a device adapted for use in connection with an internal combustion engine to render the fuel charge more highly combustible.

5 An object of the invention is to provide a device which will cause the fuel charge in the intake manifold of the engine to be transformed to ionized vapor prior to entering the cylinder.

10 Another object of the invention is to provide a device of the character described which is operated by the ignition system of the engine.

15 A further object of the invention is to provide a device of the character described which at low and normal speeds of the engine, will deliver ionized fuel to the intake manifold for mixture with the fuel charge, but at high speeds of the engine will deliver air exclusively.

20 The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may 25 adopt variations of the preferred form within the scope of my invention as set forth in the claims.

Referring to said drawings:

Figure 1 is perspective view of an engine 30 equipped with my device.

Figure 2 is a vertical sectional view taken through the device.

Figure 3 is a vertical sectional view taken on the line 3-3 of Figure 2.

40 Figure 4 is vertical sectional view taken on the line 4-4 of Figure 2.

45 As illustrated in the drawings, the device of my invention is applied to an internal combustion engine 6 of the multi-cylinder type, and is preferably attached to the manifold 7

through which the fuel charge is drawn into each engine cylinder. The fuel mixture for the major portion of the charge is preferably drawn in atomized form into the passage 8 of the manifold from a suitable carburetor 9 positioned at the mouth of the manifold.

50 The device in its preferred form comprises a housing 12 having a chamber or passage 13 therein which is adapted to communicate with the intake passage 8. As here shown the housing is formed with an externally threaded extension 14 which is arranged to be screwed into the manifold and is provided with perforations 16 which allow communication between said chamber and the passage 8.

55 Means are provided for causing a comparatively thin stream of liquid fuel to be drawn into the passage 13 when a suction obtains in any of the engine cylinders. Connecting the passage 13 with the carburetor fuel supply pipe 17 is pipe 18. The size of the stream of fuel drawn from the pipe 18 into the passage is controlled by means of an adjustable needle 19, and the admission of said fuel into the passage is controlled by a valve 21. The latter includes a ball 22 which is normally held against a seat 23 by means of a spring 24. When a partial vacuum obtains in the manifold, the ball will be raised against the resistance of the spring and a charge of fuel 60 will be drawn through the valve and discharged into the passage 13. Thus it will be clear that at each intake stroke of the cylinder pistons fuel will be drawn through said latter passage.

65 Means are further provided for causing the fuel in the passage 13 to be dissociated and ionized prior to its discharge into the manifold passage 8. In the present embodiment of the invention dissociation and ionization 70 of the fuel is effected by passing an electric current through said fuel while in passage 13. Accordingly there is preferably arranged in said passage a pair of insulated electrode points across which an electric spark is adapt- 75 80 85 90

ed to jump. The fuel when thus ionized, is drawn into the manifold and there mixes with the atomized fuel mixture coming from the carburetor, and as a result by the time the 5 fuel charge enters the cylinders it will have become thoroughly vaporized and thoroughly mixed with well distributed ionized particles. With the fuel charge in the cylinders, thus 10 rendered chemically active to such a high degree, thorough and rapid combustion of the fuel will be assured.

It will be noted that the fuel charge drawn through the manifold has now been arranged to be rendered more combustible without relying upon the heat created by the engine, 15 thus enabling the engine to be readily started when cold. Furthermore, since the fuel charge is rendered so highly combustible, greater flexibility and economy in the operation of the engine will be afforded.

In the present embodiment of the invention the device is adapted to be operatively connected to the ignition system of the engine, an electric spark being caused to jump 20 across the electrode points in the passage 13 when a spark is caused to occur in one of the cylinders. As here shown the two electrodes are connected in one conductor of the ignition circuit, leading from the timer or distributor 27 to one of the spark plugs 28 of the engine.

Means are preferably included for preventing the fuel from being drawn into the passage 13, and for causing air to be substituted 25 for said fuel in the said passage, when the engine is running at high speeds. As here shown said means comprises a valve 28 which is adapted to admit air into the passage 13 and thereby prevent the displacement of the ball 22 by the suction created in the engine 30 cylinders. The valve includes a spring pressed plunger 29 which is normally closed so as to prevent the admission of air into the passage; however, when the plunger 35 is retracted, it allows air to enter the passage 13 through perforations 31. The plunger is here shown connected to the throttle lever of the carburetor by means of a flexible rod 32 and in such manner that the lever will 40 pull said plunger to open the valve 28 when the throttle valve in the carburetor is opened a predetermined amount. It is obvious that the air valve 28 may be manually controlled 45 by the operator if desired.

50 In order that the fuel passing through the passage 13 may be inspected and its variation in density, caused by adjustment, observed, I preferably provide a mica covered opening in the housing over the area between the 55 electrode points.

I claim:

1. The combination with an internal combustion engine having an electrical ignition system, a source of fuel, a passage from said 60 source through which fuel is adapted to be

drawn into the cylinder of the engine, a secondary fuel passage leading from said source into said first passage, a normally closed valve controlling the flow of fuel to said secondary passage adapted to be opened by the suction 70 created in the cylinder, and electrode points in said secondary passage connected with said ignition system, whereby a spark will be produced across said points when ignition occurs in the cylinder.

2. In a device of the character described, the combination set forth in claim 1, characterized by means operative to cause air instead of fuel to be drawn into the secondary 80 passage when the engine is running above a predetermined speed.

3. The combination with an internal combustion engine, a passage from which the fuel charge is adapted to be admitted into the engine cylinder, a secondary fuel passage 85 leading into said first passage, a normally closed valve controlling the flow of fuel to said secondary passage adapted to be opened by the suction created in the cylinder, and means operative to relieve said suction in so 90 far as its effect on said valve is concerned when the charge of fuel drawn into said first passage from a source other than said secondary passage is more than a predetermined amount.

4. In an internal combustion engine, a fuel intake passage, means operative to supply vaporized hydrocarbon fuel to said passage, means independent of said first means normally operative to supply ionized fuel to said 100 passage, and manually operable means to effect the supply of air in lieu of said ionized fuel.

In testimony whereof, I have hereunto set my hand at Oakland, California, this 7th day 105 of February, 1924.

ALBERT J. SIEVERS.
